(57) **CLAIM**

I claim the ornamental design for a hanger pin with a positioner for a control system in an architectural covering, as shown and described.

DESCRIPTION

FIG. 1 is an isometric view looking downwardly toward a top, front, and first side of the hanger pin of the present invention;

FIG. 2 is an isometric view looking upwardly at the bottom, front, and second side of the hanger pin;

FIG. 3 is a top plan view of the hanger pin;

FIG. 4 is an elevation of the second side of the hanger pin;

FIG. 5 is a bottom plan view of the hanger pin;

FIG. 6 is a front elevation view of the hanger pin;

FIG. 7 is an elevation of the first side of the hanger pin; and,

FIG. 8 is a rear elevation of the hanger pin.
